(57) **CLAIM**

The ornamental design for a grip for an interdental brush, substantially as shown and described.

DESCRIPTION

FIG. 1 is a front view of the grip for interdental brush embodying my new design;

FIG. 2 is a right side view thereof;

FIG. 3 is a left side view thereof;

FIG. 4 is a top plan view thereof;

FIG. 5 is a bottom plan view thereof;

FIG. 6 is a rear view thereof;

FIG. 7 is a cross-sectional view taken along line 7—7 of FIG. 4;

FIG. 8 is a cross-sectional view taken along line 8—8 of FIG. 4;

FIG. 9 is a cross-sectional view taken along line 9—9 of FIG. 4;

FIG. 10 is a cross-sectional view taken along line 10—10 of FIG. 4;

FIG. 11 is a cross-sectional view taken along line 11—11 of FIG. 4;

FIG. 12 is a cross-sectional view taken along line 12—12 of FIG. 4;

FIG. 13 is a cross-sectional view taken along line 13—13 of FIG. 4;

FIG. 14 is a cross-sectional view taken along line 14—14 of FIG. 4; and,

FIG. 15 is a cross-sectional view taken along line 15—15 of FIG. 4.
